(57) **CLAIM**

The ornamental design for a remote control, as shown and described.

DESCRIPTION

FIG. 1 is a perspective view of a remote control in accordance with an embodiment of the present design;

FIG. 2 is a top plan view thereof;

FIG. 3 is a bottom plan view thereof;

FIG. 4 is an inverted top end elevation view thereof;

FIG. 5 is a bottom end elevation view thereof;

FIG. 6 is a right side elevation view thereof; and,

FIG. 7 is a left side elevation view thereof.

The broken line showing of the remote control is included for the purpose of illustrating portions of the remote control and forms no part of the claimed design.
